UNITED STATES PATENT OFFICE

WILHELM B. BRONANDER, OF MONTCLAIR, NEW JERSEY

FIRE EXTINGUISHER

Application filed July 8, 1929. Serial No. 376,747.

This invention relates to fire extinguishers. The invention relates more particularly to fire extinguishers of the type utilizing a fire extinguishing liquid, such as carbon tetrachloride.

The invention has for its salient object to provide a casing structure for housing a frangible container so constructed and arranged that the container housed therein will be protected against accidental breakage but can be readily broken when desired.

Another object of the invention is to provide an extinguisher so constructed and arranged that a plurality of separately operable containers can be housed therein.

Another object of the invention is to provide an extinguisher comprising a casing and containers mounted therein that is simple and practical in construction; comprises a minimum number of parts, and can be efficiently operated.

Further objects of the invention will appear from the following specification taken in connection with the drawings, which form a part of this application, and in which

Fig. 1 is a longitudinal sectional elevation of a device constructed in accordance with the invention;

Fig. 2 is an end view of one end of the construction shown in Fig. 1;

Fig. 3 is an elevational view, broken away, showing the central portion of the device and clamping bracket; and

Fig. 4 is a plan view of the bracket.

The invention briefly described consists of a casing having a plurality of compartments and independently operable frangible containers disposed in the compartments. The containers are so supported that they will be held against accidental breakage but can be readily and quickly broken when desired to release the fire extinguishing fluid or liquid contained therein. Further details of the invention will appear from the following description:

In the form of the invention illustrated in Fig. 1, there is shown a casing consisting of two sections A and B. Each section is tubular and has an open end 11 and a closed end 12, perforated as shown at 13. Each closed

end 12 has secured therein at the central portion thereof a metallic slug or anvil 14. If desired the anvil or slug 14 may have a barb or pointed projection 15 extending therefrom.

The open end 11 of each section is threaded as shown at 16 and the two ends 11 are threaded into a coupling having a disk or wall 17 and internally threaded sleeves 18 and 19.

Each section houses a frangible container 20 which seats at one end against a pad 21 disposed against the coupling wall 17. At the other end each container has a nipple 22 engaged by a spring 23 which seats against the closed end of the section.

The containers 20 are slidably mounted in the sections A and B and are held against accidental endwise movement therein by the springs 22.

Suitable fire extinguishing fluid or liquid such as carbon tetrachloride is sealed in each container 20.

The tubular sections and coupling may be supported in a clamp or bracket of any suitable construction. One form of bracket is shown in Fig. 4 and comprises a base 25 and two sets of resilient clamping arms 26 and 27 adapted to embrace the sections A and B outside the sleeves 18 and 19 of the coupling.

In case of fire the device is grasped and pulled away from the bracket and given a sudden longitudinal thrust in one direction. This will cause one of the containers to slide longitudinally and the nipple 22 of the container will strike the anvil or slug 14 and be broken. The fire extinguishing liquid will then escape from the container and can be sprinkled on the fire through the perforations 13. If it is found that the contents of one container is not sufficient to extinguish the fire, the other container can be broken in a similar manner and the contents can be utilized.

If desired, the nipple portion 22 of the container may be made slightly thinner than the remaining portion thereof to facilitate its breakage and the closed end 12 can be made thinner at the central portion thereof to permit this portion to be pressed in or dented in to engage the nipple.

Although one specific embodiment of the

invention has been particularly shown and described, it will be understood that the invention is capable of modification and that changes in the construction and in the arrangement of the various cooperating parts may be made without departing from the spirit or scope of the invention, as expressed in the following claims.

What I claim is:

- 10 1. A fire extinguisher comprising a casing, a frangible container movably mounted therein, said container having fire extinguishing liquid therein, a spring for holding the container against movement, and means engageable by the container for breaking the container when the container is moved in the casing against the force of the spring, the weight of the container and liquid therein being sufficient to overcome the action of the spring when the bodily movement of the casing and contents is interrupted.
- 15 2. A fire extinguisher comprising a casing, a frangible container slidably mounted therein, said container having fire extinguishing liquid therein, a spring for holding the container against movement, and means engageable by the container for breaking the container when the container is moved in the casing against the force of the spring, the weight of the container and liquid therein being sufficient to overcome the action of the spring when the bodily movement of the casing and contents is interrupted.
- 20 3. A fire extinguisher comprising a casing having a closed end, a frangible container movably mounted in the casing, said container having fire extinguishing liquid therein, a spring bearing against the closed end and the container, and means carried by the casing for breaking the container upon movement thereof against the force of the spring, the weight of the container and liquid therein being sufficient to overcome the action of the spring when the bodily movement of the casing and contents is interrupted.
- 25 4. A fire extinguisher comprising a casing having a closed end, a frangible container movably mounted in the casing, a spring bearing against said end and the container, and means carried by the casing for breaking the container upon movement thereof against the force of the spring, said casing having perforations therein to permit the escape therefrom of the contents of the container when the container is broken, the weight of the container and liquid therein being sufficient to overcome the action of the spring when the bodily movement of the casing and contents is interrupted.
- 30 5. A fire extinguisher comprising a casing having a closed end, a frangible container movably mounted in the casing, a spring bearing against said end and the container, and means carried by the casing for breaking the container upon movement thereof against the force of the spring.
- 35 6. A fire extinguisher comprising a casing having a partition wall therein, a frangible container movably mounted in the casing on each side of said wall, and a removable perforated cap at each end of the casing for closing the end thereof and confining the container therein and means at the perforated ends of said casing for breaking the containers by impact therewith.
- 40 7. A fire extinguisher comprising a casing having a partition wall therein, a frangible container movably mounted in the casing on each side of said wall and having fire extinguishing liquid therein, said casing having ends for confining the container therein, means at each end of the casing for breaking the containers by impact therewith, and resilient means engaging each container for holding the container in position in the casing, said casing being perforated at each end to permit the escape of the fire extinguishing liquid therethrough.
- 45 8. A fire extinguisher comprising a casing having a partition wall therein, a frangible container movably mounted in the casing on each side of said wall, the casing being closed at the ends, confining the container therein, resilient means engaging each container for holding the container in position in the casing, and means in the casing engageable by each container for breaking the container upon movement thereof against the action of the spring acting thereon.
- 50 9. A fire extinguisher comprising a double ended casing having a partition wall intermediate the ends thereof, a frangible container slidably mounted in each end of the casing, resilient means for yieldingly pressing said containers against the wall, and means engageable by said containers upon movement thereof against the action of said resilient means for breaking said containers.
- 55 10. A fire extinguisher comprising a double ended container having a partition wall intermediate the ends thereof, a frangible container slidably mounted in each end of the casing, a closure at each end of the casing for confining the container therein, a spring engaging each container for pressing the container against the partition wall, and means within each closure for breaking the container confined thereby upon movement of the container against the force of the spring.
- 60 11. A fire extinguisher comprising a dou-

and means carried by the casing for breaking the container upon movement thereof against the force of the spring, said end having perforations therein to permit the escape therefrom of the contents of the container when the container is broken, the weight of the container and liquid therein being sufficient to overcome the action of the spring when the bodily movement of the casing and contents is interrupted.

70 75 80 85 90 95 100 105 110 115 120 125

6. A fire extinguisher comprising a casing having a partition wall therein and a frangible container in the casing on each side of said wall, and a removable perforated cap at each end of the casing for closing the end thereof and confining the container therein and means at the perforated ends of said casing for breaking the containers by impact therewith.

7. A fire extinguisher comprising a casing having a partition wall therein, a frangible container movably mounted in the casing on each side of said wall and having fire extinguishing liquid therein, said casing having ends for confining the container therein, means at each end of the casing for breaking the containers by impact therewith, and resilient means engaging each container for holding the container in position in the casing, said casing being perforated at each end to permit the escape of the fire extinguishing liquid therethrough.

8. A fire extinguisher comprising a casing having a partition wall therein, a frangible container movably mounted in the casing on each side of said wall, the casing being closed at the ends, confining the container therein, resilient means engaging each container for holding the container in position in the casing, and means in the casing engageable by each container for breaking the container upon movement thereof against the action of the spring acting thereon.

9. A fire extinguisher comprising a double ended casing having a partition wall intermediate the ends thereof, a frangible container slidably mounted in each end of the casing, resilient means for yieldingly pressing said containers against the wall, and means engageable by said containers upon movement thereof against the action of said resilient means for breaking said containers.

10. A fire extinguisher comprising a double ended container having a partition wall intermediate the ends thereof, a frangible container slidably mounted in each end of the casing, a closure at each end of the casing for confining the container therein, a spring engaging each container for pressing the container against the partition wall, and means within each closure for breaking the container confined thereby upon movement of the container against the force of the spring.

11. A fire extinguisher comprising a dou-

ble ended removable container having a partition wall intermediate the ends thereof, a frangible container slidably mounted in each end of the casing, a closure at each end of the casing for confining the container therein, a spring engaging each container for pressing the container against the partition wall, and means within each closure for breaking the container confined thereby upon movement of the container against the force of the spring.

12. A fire extinguisher comprising a central coupling, a pair of casings connected thereto and extending in opposite directions therefrom, a container of fire extinguishing liquid movably mounted in each casing, each container being shorter in length than the length of the casing, an anvil in the outer end of each casing and a spring in the outer end of each casing adapted to normally prevent movement in the casing but to yield under the momentum of the container and liquid when the container moves in the casing.

13. A fire extinguisher comprising a central coupling having a wall and a pair of sleeves extending from said wall, a pair of casings connected to said sleeves and extending in opposite directions therefrom, a container of fire extinguishing liquid slidably mounted in each casing, each container being shorter in length than the length of the casing, an anvil in the outer end of each casing and a spring in the outer end of each casing adapted to normally prevent movement in the casing but to yield under the momentum of the container and liquid when the container moves in the casing.
